UNITED STATES PATENT OFFICE.

EUGENE COOK, OF KALAMAZOO, MICHIGAN, ASSIGNOR TO NATIONAL STANDARD COMPANY, OF NILES, MICHIGAN, A CORPORATION OF MICHIGAN.

DRILLING-MACHINE.

1,073,218.

Specification of Letters Patent. Patented Sept. 16, 1913.

Application filed June 5, 1912. Serial No. 701,746.

To all whom it may concern:

Be it known that I, EUGENE COOK, a citizen of the United States, residing at the city of Kalamazoo, county of Kalamazoo, 5 and State of Michigan, have invented certain new and useful Improvements in Drilling-Machines, of which the following is a specification.

This invention relates to improvements in 10 drilling machines.

My improvements are particularly designed by me for track drills and I illustrate and describe the same herein embodied in a track drill. Certain features are, however, 15 desirable for use in other relations.

The main objects of this invention are,— First, to provide an improved drilling machine in which the drill can be withdrawn from the work without reversing the direction 20 of its rotation,—that is, without rotating the drill backward. Second, to provide in a drilling machine an improved feed mechanism by means of which the drill may be rapidly advanced to the work or withdrawn therefrom. Third, to provide an improved drilling machine which is capable of 25 very rapid manipulation and one which is at the same time easy to operate. Fourth, to provide an improved track drill which is simple and economical in structure and at 30 the same time one which is very durable and not likely to get out of repair in use.

Further objects, and objects relating to structural details, will definitely appear 35 from the detailed description to follow.

I accomplish the objects of my invention by the devices and means described in the following specification.

The invention is clearly defined and 40 pointed out in the claims.

A structure which is a preferred embodiment of my invention is clearly illustrated in the accompanying drawing, forming a part of this specification, in which:

45 Figure I is a side elevation of a structure embodying the features of my invention, the same being shown in operative relation, the rail being shown by dotted lines. Fig. II is a detail rear view looking from the right of 50 Fig. I. Fig. III is a horizontal section taken on a line corresponding to the broken line 3—3 of Fig. I. Fig. IV is a detail vertical longitudinal section taken on a line corresponding to line 4—4 of Fig. II. Fig.

V is a detail transverse section taken on a 55 line corresponding to line 5—5 of Fig. IV. Fig. VI is a transverse section taken on a line corresponding to line 6—6 of Fig. IV. Fig. VII is a detail vertical section on a line corresponding to line 7—7 of Fig. IV. 60

In the drawing, similar reference characters refer to similar parts throughout the several views, and the sectional views are taken looking in the direction of the little arrows at the ends of the section lines. 65

Referring to the drawing, the main or base frame 1 preferably consists of side members 2 connected by suitable cross pieces 3 and 4 and the housing base 5 which extends between the side members. The side 70 members 2 project rearwardly beyond the cross piece 4 and are connected to the arms 6 on the transverse base bar 7, the arms 6 being secured to the side members 2 by bolts 8. 75

The drill holder or spindle 9 is arranged in a horizontal position, the bearing 10 in the base cross pieces 3, its rear end being supported by the feed nut 11. The feed nut 11 is arranged in a bearing 12 in the rear 80 cross piece 4. The bearing 12 is in the form of a housing adapted to receive the feed nut 11, the bearing opening into the housing 5 at its forward end and having an inverted flange or shoulder 13 at its rear end 85 for the thrust bearing balls 14. The feed nut is retained in its bearings by means of the set screw 15 which engages an annular groove 16 in the nut. The drill holder or spindle 9 is driven through the sprocket 90 wheel 17, which is splined to the spindle.

The crank shaft 18 is mounted in suitable bearings 19 and 20 carried by the upright or standard which preferably consists of members 21 and 22 which are bolted to the 95 upwardly projecting ears 23 on the base. The ears 23 are vertically slotted at 24 to receive the bolt 25. On its front end the crank shaft is provided with a sprocket wheel 26 which is connected by the sprocket 100 chain 27 to the driving sprocket 17 on the spindle. The crank 28 is arranged on the rear end of the shaft 18. The standard is provided with a hand hold 29 at its upper 105 end, the hand hold being in the form of a cross piece located above the crank shaft 18.

The spindle 9 is provided with a chuck 30 for the drill. The drill holder or spindle 9

is threaded to coat with the feed nut 11, the thread on the spindle being a left hand thread. To drive the feed nut, I provide the sprocket wheel 17 with a gear 31 and the feed nut 11 with a gear 32. Above the spindle and parallel therewith, I arrange a feed shaft 33, the shaft being journaled in bearings 34 and 35 on the front and rear cross pieces 3 and 4 of the base. A gear 36 is splined to the shaft 33 so that it may be shifted into or out of mesh with the gear 31 on the driving sprocket 17. A gear 37 is fixed to the shaft 33 and arranged in mesh with the gear 32 on the feed nut 11. These gears 31, 32, 36 and 37 are so proportioned that the speed of the feed nut exceeds slightly the speed of the spindle, and the gears are arranged so that the feed nut is driven in the same direction as the spindle. Owing to the feed screw being a left hand screw, the spindle is advanced by this variation in speed.

The gear 37 is provided with a collar or sleeve 38 having a groove 39 therein with which the forked end of the shifting lever 40 is engaged. This lever is pivoted at 41 on the housing cap 42. The outer arm 43 of the lever is bent laterally and provided with an operating rod 44 having a hand piece 45 at its upper end arranged so as to be grasped by the hand grasping the hand piece 29 on the upper end of the standard. By an upward pull the gear 36 is shifted into mesh with the driving gear 31. By pushing downward on the rod 44, the lever 43 is actuated to throw the gear 36 out of mesh with the gear 31 and the end of the sleeve 38 into contact with the side of the gear 37. This not only disengages the feed connection for the nut to the driving gear but frictionally holds the nut against rotation. With the feed nut held against rotation, the rotation of the spindle to the right or in its cutting direction, owing to the left hand feed screw retracts or withdraws the spindle, so that the spindle is retracted from the work by revolving the crank in the feeding or in the same direction as it is rotated in drilling. To advance the drill to the work, the crank is turned backward so that the spindle is rotated in the reverse direction.

With the parts thus arranged, the machine is operated as follows.—The rail engaging hooks 46 are engaged over the rail—see Fig. I where the rail is shown in dotted lines. With the gear 36 out of mesh, the drill is fed up to the rail,—that is, to the position shown in Fig. I, by turning the crank 28 backward. The gear 36 is then engaged by pulling up on the rod 44 and the crank rotated in its forward direction. With the gear 36 in mesh, the spindle is automatically fed.

When the drilling operation is complete,

the rod 44 is pushed downward to disengage the gear 36 from the gear 31, stops the feed nut and prevents its rotation. This shifting can be done without stopping the crank shaft, and as soon as the feed nut is stopped the drill is rapidly retracted although it continues to rotate in the forward direction. As soon as the point of the drill is retracted to clear the head of the rail, the machine may be tilted rearwardly in its base or swung up to disengage the hook 46, and is entirely freed from the rail.

The rotation of the drill in the forward direction while it is being retracted or withdrawn from the work is of decided advantage as it prevents burring of the cutting edges of the drill such as sometimes results from turning the drill backward while it is in the work and being retracted therefrom.

The fact that it is not necessary to reverse the rotation of the crank to retract the drill and that it is withdrawn at full speed of the screw, makes it possible to retract the drill from the rail and take the machine from the rail very quickly. The advantage of this not only from the point of being able to accomplish a large amount of work, but also in being able to quickly remove the drill from the rail to accommodate passing trains or cars, is obvious.

The hooks 46 are adjustably mounted on the hook arms 47, the hooks being longitudinally slotted at 48 to receive the securing screws 49. The hook arms 47 are connected at their forward ends by the cross bar 50. The arms 47 are secured to the frame or base 1 by means of bolts 51 and 52. The arms 47 are provided with vertical slots 53 with which the bolts 52 engage so that the arms may be swung on the bolts 51 to adjust the same for raising or lowering the hooks according to the height of the rail. By adjustably mounting the hooks upon the hook carrying arms, they may be adjusted according to the size of the rail or to accommodate various conditions found in practice. The hooks 46 are independently adjustable so that one may be made longer than the other to meet different conditions such as curves, working around frogs, and the like. The hooks are spaced a considerable distance apart so that coacting with the base, they form a firm support for the machine when resting upon the rail.

A housing cap 42 is provided for the driving gear, the cap being mounted on the base portion of the housing by means of the screw 55. The housing effectively incloses the gears to protect them from dirt and also prevent the gear being injured or broken by careless handling. The housing base 5 is adapted to receive lubricant so that the gears are kept effectively lubricated.

My improved drill is capable of very rapid operation on account of the facility

with which it can be adjusted to the work and retracted from the work. The hook 46 may be engaged with the rail and disengaged from the rail without the workman 5 bending over to manipulate the same. A further advantage is that the drills are not likely to be broken in retracting from the work and removing the machine therefrom.

I have illustrated and described my improvements in the form in which I have embodied them. Considerable variation in structural details is possible without departing from my invention as defined by the claims, but I have not attempted to illustrate 10 or describe such variations as they will be readily understood by those skilled in the art to which this invention relates from the disclosure made.

Having thus described my invention, what 20 I claim is new and desire to secure by Letters Patent is:

1. In a drilling machine, the combination with the frame comprising a horizontal portion and an upright portion, the horizontal portion being provided with a base at its 25 rear end and with downwardly facing rail engaging hooks at its forward end adapted to coact with the base in supporting the frame, the upright being provided with a handhold at its upper end; a drill spindle provided with a left hand feed screw; a driving wheel having a gear thereon splined to said spindle; a feed nut having a gear thereon; a shaft arranged parallel with said 30 spindle; a gear fixed on said shaft and meshing with said gear on said nut; a gear splined to said shaft adapted to be shifted into and out of mesh with said gear on said driving wheel; means for holding said feed 35 nut against rotation when said gear is shifted out of mesh; a shifting lever for said gear and for said means; a shifting rod provided with a hand piece adapted to be grasped in connection with the handhold of the frame upright; a crank shaft provided 40 with a crank at its rear end; and driving connections from said crank shaft to said driving wheel on said spindle.

2. In a drilling machine, the combination 50 with the frame comprising a horizontal portion and an upright portion, the horizontal portion being provided with a base at its rear end and with downwardly-facing rail engaging hooks at its forward end adapted 55 to coact with the base in supporting the frame, the upright being provided with a handhold at its upper end; a drill spindle provided with a feed screw; a driving wheel having a gear thereon splined to said spindle; a feed nut having a gear thereon; a shaft arranged parallel with said spindle; a gear fixed on said shaft and meshing with 60 said gear on said nut; a gear splined to said shaft adapted to be shifted into and 65 out of mesh with said gear on said driving

wheel; means for holding said feed nut against rotation when said gear is shifted out of mesh; a shifting lever for said gear and for said means; a shifting rod provided with a hand piece adapted to be grasped in connection with the handhold of the frame upright; a crank shaft provided with a crank at its rear end; and driving connections from said crank shaft to said driving wheel on said spindle. 70

3. In a drilling machine, the combination with the frame, of a drill spindle having a left hand feed screw; a driving wheel having a gear thereon splined to said spindle; a feed nut for said feed screw having a gear thereon; a shaft arranged parallel with said spindle; a gear fixed thereon and meshing with said gear on said nut; a gear splined to said shaft and adapted to be shifted into and out of mesh with said gear on said driving wheel and provided with a sleeve having an annular groove therein; said sleeve being adapted to hold said feed nut against rotation when said gear is shifted out of mesh; and a shifting lever engaging said 85 groove. 90

4. In a drilling machine, the combination with the frame comprising a horizontal portion and an upright portion, the horizontal portion being provided with a base at its rear end and with downwardly facing rail engaging hooks at its forward end adapted to coact with the base in supporting the frame, the upright being provided with a handhold at its upper end; a drill spindle provided with a left hand feed screw; a crank shaft; driving connections from said crank shaft to said spindle; a feed nut for said feed screw; driving connections for said feed nut adapted to drive the same in 95 the same direction as the feed screw and at a speed exceeding that of the feed screw; means for connecting and disconnecting said feed nut driving connections; and means for automatically locking said feed nut against 100 rotation when its driving connections are disconnected and also including a hand piece adapted to be grasped in connection with 105 the handhold of the frame. 110

5. In a drilling machine, the combination with the frame comprising a horizontal portion and an upright portion, the horizontal portion being provided with a base at its rear end and with downwardly facing rail engaging hooks at its forward end adapted 115 to coact with the base in supporting the frame; a drill spindle provided with a left hand feed screw; a crank shaft; driving connections for said crank shaft to said spindle; a feed nut engaging said feed screw; driving connections for said feed nut adapted 120 to drive the same in the same direction as the feed screw and at a speed exceeding that of the feed screw; and means for connecting and disconnecting said feed nut 125 130

- driving connections including means for automatically locking said feed nut when its driving connections are disconnected.
6. In a drilling machine, the combination with the frame comprising a horizontal portion and an upright portion, the horizontal portion being provided with a base at its rear end and with downwardly facing rail engaging hooks at its forward end adapted to 10 coat with the base in supporting the frame, the upright being provided with a handhold at its upper end; a drill spindle provided with a feed screw; a crank shaft; driving connections from said crank shaft to said spindle; a feed nut engaging said feed screw; driving connections for said feed nut; and means for connecting and disconnecting said feed nut driving connections including a hand piece adapted to be 15 grasped in connection with said handhold of the frame including means for automatically locking said feed nut when its driving connections are disconnected.
7. In a drilling machine, the combination with the frame provided with a base at its rear end and with downwardly facing rail engaging hooks at its forward end adapted to 20 coat with the base in supporting the frame; a drill spindle provided with a left hand feed screw; a feed nut engaging said feed screw; a crank shaft provided with a 25 crank at its rear end; driving connections for said crank shaft to said spindle; driving connections for said feed nut adapted to be 30 connected or disconnected, said feed nut being driven in the same direction as said feed screw and at a speed exceeding that of the feed screw; and means for disconnecting the 35 driving connections for said nut without stopping the crank or changing the direction of its rotation, including means for automatically locking said feed nut when its 40 driving connections are disconnected.
8. In a drilling machine, the combination of the frame; a drill spindle provided with a left hand feed screw; a feed nut for said feed screw having a gear thereon; a driving wheel for said spindle having a gear thereon; a shaft arranged parallel with said 45 spindle; a gear splined to said shaft to be shifted into and out of mesh with said driv-
- ing gear; a gear fixed to said shaft and meshing with said gear on said feed nut; and means for automatically locking said feed nut when its driving connections are 50 disconnected.
9. In a drilling machine, the combination of the drill spindle having a left hand feed screw rotating therewith; driving means for said spindle comprising a gear splined thereto; a feed nut for said feed screw; driving connections from said gear to said feed nut whereby the feed nut is driven at a speed exceeding and in the same direction as said feed screw; and means for disconnecting the 55 driving connections for said feed nut, including means for automatically locking said feed nut when its driving connections are disconnected.
10. In a drilling machine, the combination of the drill spindle having a left hand feed screw rotating therewith; driving means for said spindle comprising a gear splined thereto; a feed nut for said feed screw; means for driving said feed nut at a 60 speed exceeding and in the same direction as said feed screw and spindle; and means for stopping said feed nut while said feed screw is rotated by said spindle driving means in its forward direction whereby the 65 drill is retracted while rotating in its forward direction.
11. In a drilling machine, the combination of the drill spindle having a left hand feed screw rotating therewith; driving 70 means for said spindle and feed screw; a feed nut for said feed screw; means for driving said feed nut at a speed exceeding and in the same direction as said feed screw and spindle; and means for stopping said 75 feed nut while the feed screw and spindle are being rotated in their forward direction, whereby the drill is retracted in its forward direction.

In witness whereof, I have hereunto set 80 my hand and seal in the presence of two witnesses.

EUGENE COOK. [L.S.]
